Primary Examiner—Ralf Seifert*Attorney, Agent, or Firm*—Richard E. Oney**[57] CLAIM**

I claim the ornamental design for a jewelry accessory, as shown and described.

DESCRIPTION

FIG. 1 is a front elevational view of a jewelry accessory illustrating my ornamental design. and,

FIG. 2 is a view of the jewelry accessory of FIG. 1 shown in its environment.

The broken lines in FIGS. 1 and 2 are for purposes of illustration only and form no part of the claimed design.
